ATTORNEY

UNITED STATES PATENT OFFICE

WILLIAM W. ARNOLD, JR., OF KNOXVILLE, TENNESSEE

COMBINATION BLADE AND PIN BEATER

Original application filed December 9, 1930, Serial No. 501,123. Divided and this application filed September 16, 1931. Serial No. 563,208.

My invention relates to beaters for cotton pickers used in cleaning and lapping cotton.

The present invention is susceptible of use with cotton pickers of various types but is particularly used in connection with the apparatus for cleaning and lapping cotton disclosed in my co-pending application, serial number 501,123, from which the present invention has been divided out.

10 It is an object of the present invention to provide a combined beater and picker element of novel construction.

Another object of the invention is to provide a beater in which a blade will open the 15 cotton and hold it open until engaged by the pins which comb out the motes and waste.

A further object of the invention is to provide a three-arm beater which will be more 20 efficient in cleaning and combing the cotton while operating at a slower speed than usual.

A still further object of the invention is to provide a combination beater and picker that will retain the advantages of both blade and 25 pin beaters but will eliminate the disadvantages thereof.

Other objects and advantages of the invention will become apparent during the course 30 of the following description when read in conjunction with the accompanying drawing which forms a part of this specification and in which:

Figure 1 is a vertical sectional view of a portion of a picker unit showing my improved beater in operative relation, and

35 Figure 2 is a top plan view of the beater.

Referring now more particularly to the drawing in detail, 5 indicates the beater power shaft upon which is mounted a plurality of sets of radiating arms 6. Each set preferably includes three equally spaced arms but this number may be varied depending upon the speed of operation. The arms 6 are formed with and radiate from hubs 7 which are mounted at spaced intervals on the shaft 5.

40 A bar or plate 8 is mounted upon the extremities of aligned arms 6, the plates being secured to the arms by means of screws 9. Each of the plates 8 is provided with a plurality of rows of pins 10, the rows extending 45 from end to end of the plates and the pins of

succeeding rows being staggered with respect to the pins in the preceding row. An example of a preferred spacing would be to have pins in each row one inch apart and the rows one-fourth inch apart with the 55 pins in each succeeding row offset one-fourth inch from the center of the pins in each preceding row. This arrangement would place each pin in the fourth row directly behind a pin in the first row and each pin in the fifth 60 row behind a pin in the second row, etc.

A blade 11 is mounted on the forward edge of each of the plates 8, said blade being fastened in position by means of screws 12 which pass through the plates 8 and engage the arms 6. The forward edge of the blades 11 project beyond the forward edge of the plates 8 and are bevelled off on their under sides at 13 to produce a sharper edge for engaging the cotton as it merges from between the feed 70 rolls 14 and 15 of the picker unit 16. The pins 10 extend about one-sixteenth of an inch beyond the outer surface of the blades 11.

In operation, the blades 11 strike the end 75 of the cotton sheet as it is fed and held by the feed rolls 14 and 15, opening the cotton and pressing it down against the feed roll 14. The impact of the blow from the blades 11 separates the motes and heavy waste and 80 sends them through the grid bars 17 of the unit 16, while the lighter cotton fibers are carried over the grid bars to the screen section 18.

Instantly after the blade 11 presses the sheet down against the feed roll 14 and while 85 it is still in this position, the pins 10 pass through the outer surface of the sheet with a gentle combing action. The combing action thus effected is more efficient than that possible with an ordinary pin beater since the 90 sheet is not torn by reason of the pins going too deep, which is a common fault of other types of pin beaters. The pins 10 in addition to combing out the fibers will also remove 95 motes and waste which are not already removed by the blade 11.

Although a preferred embodiment of the invention has been shown and described, it will be understood that various changes in the details of construction may be made with- 100

out departing from the spirit of the invention as defined by the appended claims.

I claim:

5. 1. A combination blade and pin beater for cleaning cotton or other fibers including a plurality of rotatable arms, a blade mounted at the forward edge of each of said arms and a plurality of pins rearwardly of each of said blades, the outer surface of the blade being located beyond the inner ends of the pins.
10. 2. A combination blade and pin beater for cleaning cotton or other fibers including a plurality of rotatable arms, a blade carried at the forward edge of said arms, a plate also carried by said arms, and a plurality of pins projecting from the plate and located rearwardly of said blade, the outer surface of the blade being located beyond the inner ends of the pins.
15. 3. A combination blade and pin beater for cleaning and opening cotton including a plurality of rotatable arms, a plurality of pins supported by said arms and a cotton deflecting blade in advance of said pins, the outer surface of the blade being located beyond the inner ends of the pins.
20. 4. A combination blade and pin beater for cleaning and opening cotton including a rotatable arm, a plate mounted on said arm, a plurality of rows of pins carried by and projecting from said plate and a blade mounted forwardly of the first row of said pins whereby to deflect the fibers to be cleaned immediately prior to subjecting them to the combining action of said pins, the outer surface of the blade being located beyond the inner ends of the pins.
